DESIGN FOR A PIANO CASE

William Millington, Grand Rapids, Mich., and Wilbur M. Day, Norwood, Ohio, assignors to The Baldwin Company, Cincinnati, Ohio, a corporation of Ohio

Application September 10, 1948, Serial No. 148,534

Term of patent 14 years

(Cl. D56—9)

To all whom it may concern:

Be it known that William Millington and Wilbur M. Day, citizens of the United States of America, residing at Grand Rapids, county of Kent, State of Michigan, and Norwood, county of Hamilton, State of Ohio, respectively, have invented a certain new, original, and ornamental Design for a Piano Case, of which the following is a specification, reference being had to the accompanying drawing, forming a part thereof.

The drawing is a perspective view of a piano case, showing my new design.

We claim:

The ornamental design for a piano case, substantially as shown.

WILLIAM MILLINGTON.
WILBUR M. DAY.
